Attorney.

UNITED STATES PATENT OFFICE.

JESSE T. MABBEY, OF FOREST, OHIO, ASSIGNOR OF TWO-THIRDS TO DANIEL ASIRE AND JOHN F. NYE, OF SAME PLACE.

RAILROAD-CROSSING.

SPECIFICATION forming part of Letters Patent No. 394,868, dated December 18, 1888.

Application filed April 27, 1888. Serial No. 272,054. (No model.)

To all whom it may concern:

Be it known that I, JESSE T. MABBEY, a citizen of the United States of America, residing at Forest, in the county of Hardin and 5 State of Ohio, have invented certain new and useful Improvements in Railroad-Crossings, of which the following is a specification, reference being had therein to the accompanying drawings.

10 This invention pertains to certain new and useful improvements in railroad-crossings, having for its object the provision of simple and highly-efficient means for readily and easily shifting pivoted sections of a main line 15 into a plane coincident with the rails of the cross-line, whereby a train on one line is permitted to pass over the track of another line.

15 The invention consists in pivoted heads or wheels carrying each a section of a rail, said 20 heads or wheels being connected together by means of chains, whereby they are all operated simultaneously; and the invention comprises the detail construction, combination, and arrangement of parts, substantially as 25 hereinafter fully set forth, and particularly pointed out in the claims.

In the accompanying drawings, Figure 1 is a plan view of my invention. Fig. 2 is a detail sectional view thereof on the line $x x$, 30 Fig. 1. Fig. 3 is a detail perspective of one of the fish-plates, and Fig. 4 is a detail plan view of the rail bed or frame.

Referring to the drawings, A designates a main track or line crossed at right angles by 35 a cross-line, A'.

B is a square-shaped frame or bed, composed of four flat metallic bars rigidly secured to or formed with each other, the same being secured upon the ordinary ties, as shown. 40 Upon the upper surfaces of the bars of this frame or bed are secured the rails at the point of crossing. The object of this frame or bed is to prevent lateral displacement of any of the rails at this point, and in the event of one 45 rail being deflected from its proper position the other rails will also move therewith, whereby all the rails at the point of crossing always maintain the same relative position.

C C indicate four heads or wheels located 50 at the point of intersection of each rail with

the adjoining rail of the cross or main track. Each head or wheel is composed of a circular body portion having a circumferential groove or recess, d , and from the under side of said head or wheel projects a short stud or pin, d' , 55 which is passed through an aperture in the frame or bed B into a correspondingly-shaped hole or aperture in the tie located at that point, as shown in Fig. 2. Upon the upper surface of each head or wheel C projects a rail-section, d^2 , as shown, which is designed to fit flush with the opposite ends of the rail of either the main or cross track, according to the position it is made to occupy.

D D are clips having pronged or forked 60 ends, through which spikes are driven for retaining the same in position. These clips have upwardly-projecting overhanging portions $e e$, which are designed to rest upon the upper surfaces of the heads or wheels C for 65 holding the same in position, two of said clips being applied to each head or wheel and placed diagonally opposite each other. The side edges of the overhanging portions of 70 these clips are beveled, as shown, against 75 which beveled portions bear the side edges of the rail-sections of the heads or wheels, according to the position occupied by the latter, said beveled portions of the obliquely-arranged clips preventing the movement of said 80 heads or wheels too much to one side.

To each head or wheel C, within the circumferential groove thereof, is secured a section of a chain, F, the opposite ends of each section being connected by means of turn-buckles 85 $f f'$, in one end of each of which works a threaded rod, f' , connected at its outer end to the end of each adjoining section. By means of this connection any slack in the chain can be readily and easily taken up. 90

A swivel-loop, G, is employed for connecting one end of one section of the chain F to an arm, g , to the other end of which the other end of said chain is connected. A threaded rod, g' , works in the end of this swivel-loop 95 G for drawing the chain to the proper tension.

H is a pivoted post hinged to a stationary post, h , and to an arm attached to the lower end of this post is connected the outer end of a long arm, h' , pivotally secured at its 100

other end to one end of a lever, h^2 , the other inner end of said lever being connected to the arm g , before referred to.

The usual signal is secured to the outwardly-projecting rod I.

From the foregoing description it will be seen that when the device occupies the position shown in full lines, Fig. 1, the rail-sections of the heads or wheels will be coincident with the ends of the rails of the main line A, and by shifting the parts into the position shown in dotted lines said rail-sections will be coincident with the ends of the rails of the cross-line, as is obvious, the shifting of said heads or wheels being effected by simply turning the pivoted post II at right angles to the position previously occupied.

The advantages of my invention will be apparent to those skilled in the art to which it appertains, and it will be seen that the same is extremely simple, cheap, and durable, that it employs but few parts, is void of all complication, and hence is not liable to readily get out of order. It will also be seen that my invention embodies advantages in points of durability, general efficiency, and inexpensiveness.

It is obvious that my invention is applicable to double tracks, a mere duplication of and slight addition to the parts described being necessary.

I claim as my invention—

1. As an improvement in railroad-crossings, the series of heads or wheels connected by chains and the lever for operating said heads or wheels, substantially as shown and described.

2. As an improvement in railroad-crossings, the heads or wheels having studs or pins projecting therefrom and provided with circumferential grooves, the chains connecting said heads or wheels, and the means for operating the same, substantially as shown and described. 40

3. As an improvement in railroad-crossings, the heads or wheels pivotally secured in position and the clips having upwardly-projecting overhanging portions for securing said heads or wheels in position, substantially as shown and described. 45

4. As an improvement in railroad-crossings, the heads or wheels having the chains connected thereto and the turn-buckles having threaded rods connecting the ends of the sections of said chains, substantially as shown 50 and described.

5. The herein-described improvement in railroad-crossings, comprising the pivoted heads or wheels having rail-sections secured thereto and provided with circumferential grooves, the chains secured in said grooves, the turn-buckles having the threaded rods working therein, the clips securing said heads or wheels in place, the lever, and the hinged post connected to said lever, substantially as shown and described. 55

In testimony whereof I affix my signature in presence of two witnesses.

JESSE T. MABBEY.
